UNITED STATES PATENT OFFICE

2,655,746

UNITARY STEAM AND TEMPERATURE
CONTROL FOR STEAM IRONS

Donald L. McFarland and Walter E. Moore, Stratford, Conn., assignors to General Electric Company, a corporation of New York

Application April 25, 1951, Serial No. 222,806

4 Claims. (Cl. 38—77)

1

This invention relates to pressing irons of the type which include steam generating systems so arranged that the irons may be used either as steam irons or as conventional "dry" flatirons. More particularly, this invention relates to the temperature and steam control means employed in such irons.

It is quite important in these irons that some means be provided whereby the steam produced is always of the proper quality for pressing clothes. Specifically, the steam must be moist enough to wet the clothes, but must not be so moist as to contain actual drops of water, since such drops will usually stain the clothes. In irons of this sort, the most practical way of controlling the quality of the steam is to supply feed water to the steam generating chamber at a constant rate and then control the temperature of the generating chamber. Since these chambers are customarily heated from the soleplate of the iron, the quality of the steam then actually depends on the soleplate temperature. This, however, leads to difficulty in that steam of the correct quality can be produced only in a limited range of soleplate temperatures, whereas the irons must supply a wide range of soleplate temperatures in order to be used as dry flatirons.

It is a general object of this invention, therefore, to provide a new and improved iron so constructed that water can be supplied to the steam generating chamber in only a limited portion of the soleplate temperature range; and in the fulfillment thereof, it is a more specific object of this invention to provide such an iron in which the steam generating means and the temperature-regulating means are operated from the same unitary control member.

In accomplishment of the foregoing objectives, a new and improved steam iron is constructed so that its soleplate temperature is controlled by the angular position of a rotatable shaft and so that its steam generating means are controlled by a valve positioned between a liquid reservoir and a steam generating chamber. The operating means for the temperature control shaft and the valve are combined in a single unitary operating lever which is pivotally mounted on the rotatable shaft to have motion in two discrete planes. Arcuate movement of this lever in a plane transverse to the shaft axis causes rotation of the

2

shaft to operate the temperature control device, while pivoting of the lever in a plane extending across the above transverse plane actuates mechanical connections which open and close the valve. In order to insure that steam is generated only at the correct soleplate temperature, a cam surface is provided which allows pivotal motion of the operating lever to the steam actuating position at only one angular position of the shaft.

10 The features of this invention which are believed to be novel are set forth with particularity in the appended claims. The invention itself, however, both as to organization and mode of operation, together with further objects and advantages thereof, may be best understood by reference to the following description to be taken in conjunction with the accompanying drawing in which:

Fig. 1 is a side elevation view of a pressing iron 20 embodying this invention, a portion of the iron being shown in vertical section taken along its longitudinal axis; Fig. 2 is a sectional view taken along the line 2—2 of Fig. 1; and Fig. 3 is a fragmentary sectional view taken on the line 3—3 25 of Fig. 2.

Referring to the drawing, therein is illustrated an electrically heated steam iron of the type generally described in the copending application of Frank E. Finlayson, Serial No. 696,298, filed September 11, 1946 (now Patent 2,557,732), and the application of Frank E. Finlayson, Serial No. 69,756, filed January 7, 1949 (now Patent 2,587,608), both of which patents are owned by the General Electric Company the assignee of the instant application. In such an iron the pressing surface is formed by the bottom of a soleplate 1. Embedded in the soleplate is an electrical heating element which preferably is of the sheathed type, and here comprises a helical resistance conductor 2 mounted within an outer metallic sheath 3 and held in spaced relation to the sheath by an electrically insulating heat-conducting mass 4, such as highly compressed granulated magnesium oxide. The heating element is roughly in the shape of a U having its bight at the forward or pointed end of the iron and having its legs extending toward the rear end of the iron.

The temperature controlling mechanism and 50 the steam generating system of the iron are

mounted on soleplate 1 and are covered by a shell 5 which is also mounted on the soleplate. The shell is attached to the soleplate by a pair of transversely spaced bolts 6 which are screwed into the tapped bosses 7 formed integrally with the soleplate, and it extends rearwardly from the soleplate to provide a heel rest member for the iron. Closing the space lying between the rear extremities of the soleplate and the shell is a plate 8 which is secured to the soleplate by means of screws 9 and extends outwardly therefrom to engage the inner surface of the shell.

Mounted on top of shell 5 is a handle 10 which is preferably formed of a heat insulating material such as a phenolic condensation product. In order that it may be somewhat thermally insulated from shell 5, the handle is supported in spaced relation to the shell, the front support being provided by a portion of the steam generating system, as will be more fully explained hereinafter, and the rear support being provided by a pair of upright bosses 11 formed integrally with shell 5. The handle is secured in place by screws (not shown) which extend upwardly through bosses 11.

In effect, the handle includes three distinct portions, a hand grip portion 12, a front support portion 13 and a rear support portion 14. The rear support portion is provided with a protuberance 15 which together with the rear extremity of shell 5 forms a heel rest or support whereon the iron may be upended when not in use; and the front support portion is provided with a vertically extending recess 16 in which is positioned a portion of the steam generating system.

Thus, extending into recess 16 through an aperture 17 in shell 5 is a reservoir member 18. Means for filling this reservoir is supplied by an open end tube 19 which extends through a recess 20 in handle portion 13, and an outlet for emptying the reservoir into a steam-producing chamber is supplied by an orifice member 21 which is threaded into a hole in the base of the reservoir. Besides being the water storage member for the steam-producing system, reservoir 18 also serves as the front support for handle 10 through its contact with tube 19. The support for reservoir 18 itself is provided by aperture 17 and orifice member 21. In order to secure a watertight seal at the lower end of the reservoir, a bushing 22 is threaded to orifice member 21 below the reservoir and gasket material 23 is positioned to be compressed between the bushing and the reservoir.

Bushing 22, which actually supports orifice 21 and thus the front end of handle 10, is in turn mounted on a hood 24 and a cover plate 25 and is attached thereto by any suitable means. The lower extremity of orifice member 21, however, extends through an aperture between the hood and the cover plate. Hood 24 and cover plate 25 are secured to soleplate 1 by any suitable means such as screws 26 and together with a recess 27 formed in the upper surface of the soleplate define a steam-generating chamber 28. In order to prevent the escape of steam from the chamber, a gasket 29 is positioned between the soleplate and the edges of the hood and the cover plate.

Mounted below orifice member 21 is a trough 30 which carries any water flowing through the orifice 31 in member 21 over into recess 27. The recess is, of course, heated by the soleplate during operation of the iron, and if the soleplate is at the right temperature, any water flowing

into the recess will be immediately flashed into steam of the correct quality. From recess 27 a circuitous passage (not shown) conducts the steam to the steam discharge ports 32.

5 In accordance with this invention, the flow of water into the steam generating chamber 28 is controlled by a valve member or plunger 33 on whose lower end is mounted a needle 34. When plunger 33 is in its lower position, as viewed in 10 Fig. 1, its lower end engages orifice member 21 and prevents any water flow from the reservoir into the steam chamber. However, when plunger 33 is moved upwardly to the position indicated by the dotted lines, its lower end is pulled clear 15 of the orifice member 21 and a flow of water into the steam chamber may occur. Orifice 31, of course, regulates the rate of water flow into the steam generating chamber to the correct value when the valve is open. The needle or clean-out pin 34 is forced through the orifice 31 when the valve is closed and thereby cleans out any scale or deposit which may have formed in the orifice. A spring 35 disposed around plunger 33 and compressed between the upper surface of 25 reservoir 18 and a flange 36 mounted on the plunger serves to bias the plunger downwardly and thereby keep the valve closed unless an external force is applied to the plunger.

In order to provide means for applying such 30 a force, the upper end portion of plunger 33 is extended out of reservoir 18 through an aperture 37 provided in the reservoir roof, and an L-shaped member 38 is secured to the portion of the plunger lying outside the reservoir. Member 38 is mounted so that its base portion 38a, to which plunger 33 is attached, extends transversely to the plunger while its shaft portion 38b extends downwardly toward shell 5. Positioned 35 to engage the end of shaft portion 38b is an operating lever 39 which is pivotally mounted by a pin 40 on a rotatable shaft 41. Lever 39 is biased by spring means 42 so that ordinarily it does not engage member 38. However, upon a sufficient force being applied to the knob 43, which is mounted on the end of the lever opposite from member 38, the lever is pivoted against the spring bias to move shaft portion 38b upwardly and thereby open the needle valve.

Besides being the actuating member for the 40 steam system, lever 39 also serves as the operating control for regulating the temperature of soleplate 1. Specifically, the angular position of shaft 41, which is changed by moving knob 43 in an arcuate path transverse to the path of its pivotal motion and substantially perpendicular to the axis of shaft 41, determines the setting of a thermostatic control device included in the iron heating circuit. To insure that steam may be produced at only one soleplate temperature, a cover plate 44 is positioned beneath the path of arcuate motion of shaft 43 so as to form a cam surface preventing downward movement of the knob, i. e., pivotal movement of lever 39, except at one angular position of shaft 41. Thus, knob 43 may be depressed sufficiently to operate 45 the needle valve only when it is over the recess provided in cover plate 44.

One wall 45a of recess 45 is sloped inwardly, while an aperture 46 is cut in the opposite wall. Wall 45a and aperture 46 cooperate with a shoulder 47 formed on the side of knob 43 to supply means to automatically latch the knob down in the steaming position. As knob 43 is depressed, it slides down and arcuately along sloped 50 wall 45a so that when the knob reaches the bot-

tom of the recess, shoulder 47 has moved under the upper lip of aperture 46. Then, as the knob is released, shoulder 47 catches upon the upper lip of aperture and holds the knob in the steaming position. Thus, the latch-down is automatic, the operator needing only to depress the knob to lock the knob in the steaming position.

The temperature regulating device controlled by the angular position of shaft 41 may be any of those well-known to the art, since it does not constitute part of this invention. A preferred device, however, is illustrated in the diagram, and is fully disclosed and claimed in the co-pending application of Frank E. Finlayson for "Thermostatic Switch for Automatic Flatirons," Serial No. 165,216, filed May 31, 1950, Patent 2,602,873, issued July 8, 1952, and assigned to the same assignee as the present invention. In the diagram, shaft 41 is rotatably supported by a recess 48 in handle 10 and by a support member 49 which is secured to the top surface of soleplate 1 by a pair of screws 50. Member 49 also serves as the bearing for a rotatable cam plate 51, and for that purpose is provided with a plurality of upright bosses (not shown) which engage the under surface of the cam plate.

Cam plate 51 is held on member 49 by means of a spring 52 which is formed integrally with the cam plate. Spring 52 extends outwardly from one edge of the cam plate, and, thence, is folded underneath member 49. In the end of spring 52 extending under member 49 is positioned an aperture which fits onto an extrusion 53 formed on member 49. The action of spring 52 thus holds cam plate 51 against the upright bosses formed on the top surface of member 49 but permits the cam plate to be rotated by shaft 41 to which it is attached for that purpose. Mounted on top of cam plate 51 is a cam member 54 having a cam surface 55 on its outer periphery, and disposed to cooperate with this cam surface is a lever 56. Lever 56 is pivotally mounted by means of a pair of down-turned ears 57 on a shaft 58, the shaft itself being supported by the side walls 59 of a U-shaped base plate 60. The aforementioned support member 49 is actually a part of base plate 60, so that screws 50 also serve as the means for securing base plate 60 to sole-plate 1. It is the bight of base plate 60 through which screws 50 are disposed, the legs of the base plate extending rearwardly therefrom and side walls 59 extending upwardly from the legs.

An adjusting screw 61 is threaded into the end of lever 56 opposite from the end cooperating with cam surface 55, and mounted on the lower end of this screw is a stop 62 formed of electrically insulating material. Stop 62 engages the movable portion of an electrically conducting switch arm 63 which has a movable portion and a portion fixed to the transverse section 64 that joins together the rear ends of upright walls 59 of the base plate. The switch arm is, however, insulated from the plate by some insulating material, such as sheet mica. Mounted on the free end of switch arm 63 is a contact 65 and disposed to cooperate with contact 65 is a second contact 66 mounted on an electrically conducting spring switch arm 67. Switch arm 67 is secured to the other side of section 64 from switch arm 63 and is insulated from the section by a sheet of mica or other insulation.

Spring switch arm 63 is biased to move contact 65 upwardly while spring switch arm 67 is biased to move contact 66 downwardly. The bias of arm 63 is, however, greater than that of arm 75

67 so that the position of stop 62 determines the position of both switch arms by limiting the movement of arm 63. As is disclosed in the aforementioned Finlayson Patent 2,602,873, the cooperating contacts 65 and 66 are connected in series with resistance conductor 2 and the power supply terminals of the iron so that heating of the iron is controlled by the opening and closing of the contacts. Thus, for example, switch arm 63 and one terminal 68 of conductor 2 are connected together while switch arm 67 and the other terminal of conductor 2 (not shown) are connected to opposite supply terminals.

The opening of the contacts is accomplished by a bimetallic temperature-responsive bar 69 formed of two metals having dissimilar temperature coefficients of expansion rigidly secured together lengthwise in any suitable way, as by welding. Preferably, and as shown, the bar will be formed of two reversed sections in order to minimize temperature overshoot in the fashion described and claimed in the U. S. patent to R. A. Winborne, No. 2,128,869 dated August 30, 1938. The one end of bimetallic bar 69 is firmly secured between base plate 60 and a heat-conducting clamping block 70, being joined to both of these members by a rivet 71 and to the base plate alone by a rivet 72. This assembly allows the thermostat to be calibrated as a unit outside the iron and then later be assembled within the iron by screws 50. The remainder of bar 69 extends rearwardly over a cavity 73 formed in soleplate 1 and has an upright switch actuator 74 mounted on its end. Actuator 74 is formed of a refractory electrically insulating material and comprises a tube which is closed at its upper end. This actuator is mounted on bar 69 by means of a right angle bracket 75 to which it is secured by a suitable cement and which, in turn, is secured to the bar by welding or some other suitable means. Bar 69 is so constructed that its free end carrying actuator 74 moves upwardly upon the heating of soleplate 1 and moves downwardly as the soleplate cools.

The actuator is spaced below spring switch arm 67 and engages the arm as it moves upwardly in response to the heating of soleplate 1 by current flowing in conductor 2. The continuing movement of the actuator then moves the arm upwardly against its downward bias and thereby opens contacts 65 and 66. The opening of the contacts breaks the circuit to conductor 2 and allows the soleplate to cool, causing actuator 74 to move downwardly. When the actuator has moved a sufficient distance, it allows switch arm 67 to reclose the contacts and re-energize the heating circuit. This, of course, makes the soleplate heat up once again and causes actuator 74 to move upwardly until the contacts are opened. Thus, the action of actuator 74 as mounted on thermostatic bar 69 causes the soleplate temperature to cycle around a mean value.

This mean value of soleplate temperature is controlled by means of shaft 41. As shaft 41 is rotated by lever 39, cam surface 55 causes lever 56 to pivot on shaft 58 moving stop 62 either upwardly or downwardly. Since stop 62 engages switch arm 63, a downward movement of stop 62 forces switch arm 63 and thus contact 65 to also move downwardly, while an upward movement of the stop allows the switch arm 63 also to move upwardly, due to its spring bias. This spring bias, as previously mentioned, is greater than the downward bias of switch arm 67 and therefore forces switch arm 67 to also move up-

wardly with arm 63. Moreover, as stop 62 moves switch arm 63 downwardly, switch arm 67 also moves downwardly due to its own bias and keeps the contacts closed, except when it is engaged by actuator 74.

The vertical spacing between switch arm 67 and actuator 74, when the iron is cold, is thus dependent upon the position of stop 62 and thereby is dependent on the angular position of shaft 41. The position of shaft 41 is, of course, controlled by the arcuate position of operating lever 39 so that actually the spacing between switch arm 67 and actuator 74 is regulated by lever 39. It is this spacing that determines at what temperature the iron is to operate, for the greater is the spacing, the greater is the soleplate temperature required for thermostatic bar 69 to move actuator 74 sufficiently that it may engage switch arm 67 to open the contacts.

In order to provide means for opening the heating circuit at the discretion of the operator, the device is so constructed that stop 62 at its point of maximum downward excursion moves contact 65 downwardly beyond the lowest point to which the downward bias of switch arm 67 carries contact 69, i. e., the contacts do not touch at one extreme arcuate position of lever 39. As is indicated in Fig. 2, the heating circuit of the iron may be de-energized by moving lever 39 to its extreme left-hand arcuate position, while various soleplate temperatures ranging consecutively from the lowest to the highest may be obtained by moving the lever from that point to its extreme right-hand arcuate position. The terms "left-hand" and "right-hand" refer to the lever as viewed from the pointed end of the iron. For the convenience of the housewife, the various arcuate positions of the lever are marked with the respective fabrics for which the temperatures produced thereat are the most suitable. Similarly, the lever setting for steam is plainly marked. Of course, even though the operator might disregard the steam marking, she still could not apply steam except at the correct temperature, due to the cam surface provided by the cover plate.

As previously mentioned, this invention is not limited to the particular temperature control device described above, since the new and improved unitary temperature and steam control can be used with any thermostatic device whose setting is controllable by the angular position of a rotatable member. Moreover, various details of the steam generating system could be changed and still permit its actuation by a control formed according to this invention. Thus, while there has been described what at present is considered to be the preferred embodiment of this invention, it will be obvious to those skilled in the art that numerous modifications and alterations may be made therein without departing from the invention, and it is, therefore, intended in the appended claims to cover all such modifications and alterations as fall within the true spirit and scope of this invention.

What we claim as new and desire to secure by Letters Patent of the United States is:

1. In an iron, a water reservoir, a steam generator, a valve providing liquid flow control from said reservoir to said generator, electrical means for heating said reservoir, a rotatable control member for regulating the heating from said electrical means upon rotation of said member, a lever pivotally mounted on said control member transversely of said member to pivot in a

plane including the axis of rotation of said member and adapted to turn said member by arcuate movement thereabout and therewith in a plane transverse to said axis, a cam surface positioned under the path of said arcuate movement, said surface limiting pivotal movement of said lever to a predetermined angular position of said rotatable member, and mechanical connections for operating said valve in response to pivotal movement of said lever.

2. In an iron, a water reservoir, a steam generating chamber, a valve providing liquid flow control between said reservoir and said chamber, an electrical circuit for heating said chamber, a rotatable member for controlling the current in said heating circuit, a lever pivotally mounted on said member to have limited pivotal motion in a plane including the axis of rotation of said member and adapted to turn said member by arcuate movement in a plane substantially at right angles to said axis, a plate disposed under the path of said arcuate movement and having a recess adapted to receive said lever extending through a limited portion of said arcuate path, said plate limiting pivotal movement of said lever to said limited portion, and a mechanical connection between said lever and said valve to operate said valve upon pivotal movement of said lever.

3. In an iron, a water reservoir, a steam generating chamber, a valve providing liquid flow control between said reservoir and said chamber, an electrical circuit for heating said chamber, a rotatable member for controlling the current in said heating circuit, a lever pivotally mounted on said member to be pivotally movable between a pair of positions in a plane including the axis of rotation of said member and adapted to turn said member by arcuate movement in a plane substantially at right angles to said axis, a spring biasing said lever to one of said pivotal positions, a mechanical connection between said lever and said valve to operate said valve upon pivotal movement of said lever to the other of said pivotal positions, a knob mounted on said lever and provided with a shoulder, a plate disposed under the path of said arcuate movement and limiting movement of said lever to said other pivotal position to a limited portion of said arcuate path, said plate having a recess in said limited portion for receiving said lever and said knob, one wall of said recess being sloped inwardly and the wall opposite to said one wall being provided with an aperture, said knob moving along said sloped wall upon pivotal movement of said lever to cause said shoulder to move into said aperture to latch said lever in said other pivotal position.

4. In an iron, a water reservoir, a steam generating chamber, a valve between said reservoir and said chamber having a closed position and having an open position to permit water to flow into said chamber, an electrical circuit for heating said chamber, a rotatable member for controlling the current in said chamber, a lever pivotally mounted on said member to be pivotally movable between a pair of positions in a first plane and adapted to turn said member by arcuate movement in a plane transverse to said first plane, a spring biasing said lever to one of said pivotal positions, a mechanical connection between said lever and said valve to operate said valve to said open position upon pivotal movement of said lever to the other of said pivotal positions, a knob mounted on said lever and provided with a

shoulder, a plate disposed under the path of said arcuate movement and limiting movement of said lever to said other pivotal position to a limited portion of said arcuate path, said plate having a recess in said limited portion for receiving said lever and said knob, one wall of said recess being sloped inwardly and the wall opposite to said one wall being provided with an aperture, said knob moving along said sloped wall upon pivotal movement of said lever to cause said shoulder to move into said aperture to latch said valve in said other pivotal position whereby said valve is held in said open position.
